ELECTRIC SWITCH

Edwin Stewart, Philadelphia, Pa.

Application September 17, 1937, Serial No. 164,409

10 Claims. (Cl. 200—48)

This invention relates to an improved electric switch construction, and has for its principal object the provision of a novel structure which is simple in construction, economic to manufacture, and which operates in a simple and efficient manner.

More particularly, the invention relates to that type of switch structure wherein the switch blade is moved longitudinally into or out of contact with the switch jaws, and is rotated to or from the open position. By this invention there is provided a switch structure of this type employing a novel blade supporting and operating structure comprising pivotal arms or links.

Another object of the invention, therefore, is to provide a switch structure in which there is employed a novel combination and arrangement of arms or links to support the blade and to effect the desired movement of the blade.

A further object of the invention is to provide a switch structure which employs elements that operate in a positive manner and which avoids the use of elements that are prone to stick, such as wedges, cams, etc.

Other objects and features of the invention will appear hereinafter. In the accompanying drawings:

Fig. 1 is a side elevational view of the switch in closed position;

Fig. 2 is a plan view of the same;

Fig. 3 is an enlarged plan view of the linkage mechanism;

Fig. 4 is a perspective view of the linkage mechanism;

Fig. 5 is a sectional view taken along line 5—5 of Fig. 3;

Fig. 6 is a side elevational view of the linkage mechanism in an intermediate position during opening or closing of the switch; and

Fig. 7 is a similar view of the mechanism in the open position of the switch.

Referring to Figs. 1 and 2, there is shown the usual switch supporting structure comprising a support 1, a stationary insulator 2 carrying the switch contacts or jaws 3, a stationary insulator 4 carrying the switch blade 5 which cooperates with jaws 3, and a rotatable insulator 6 which actuates the blade through the crank 7 and the link 8. The blade is connected electrically to the bar 9 by means of the flexible conductor 10. In operation, the blade moves longitudinally until its end is fully withdrawn from the jaws 3, as shown in dot and dash outline, and then the blade is moved pivotally to open position as described hereinafter.

In accordance with the present invention, a plate 11 is mounted on insulator 4 and is provided with a pair of similar spaced upstanding supporting lugs 12 (see Figs. 3 and 4) and a third supporting lug 13 disposed centrally and for-

wardly of the lugs 12, as shown in Fig. 3. A pair of similar arms 14 are pivotally attached to lugs 12 at pivots 12a whose axes are aligned one with the other. The arms 14 converge at their forward ends which are pivotally attached to a link 15 at pivot 16. The opposite end of link 15 is bifurcated and is pivotally attached to the blade at pivot 17. Intermediate their ends, the arms 14 are pivotally attached to similar links 18 at pivots 19 which are axially aligned. The other ends of links 18 are pivotally attached to the blade at pivot 20. Thus the arms 14, the links 15 and 18, and the blade form a quadrilateral. Links 21 are pivotally attached to lug 13 at pivot 22, and the other ends of these links are pivotally attached to the blade at the pivot 20.

The distance between the common axis of pivots 12a and the common axis of pivots 19 is equal to the distance between the axes of pivots 20 and 22. The distance between the common axis of pivots 19 and the axis of pivot 20 is also equal to the distance between the axes of pivots 20 and 22. The reason for this relation will appear presently. When the switch is closed, the pivots 19 are aligned axially with pivot 22, as will be seen from Fig. 3. When the switch is in open position, the pivot 20 is aligned axially with pivots 12a, as will be seen in Fig. 7.

Assuming that the switch is closed and considering the opening operation, as the crank 7 is rotated, the link 8 exerts a pull longitudinally of the blade, causing the blade to move from right to left as viewed in Figs. 1 and 5. The links 15 and 18 rock about their pivots 16 and 19, and at the same time the links 21 rock about their stationary pivot 22, the arms 14 remaining in the position shown in Figs. 1 and 5. Since the pivots 19 are substantially aligned with pivot 22 at this time, and since the radial distances between these pivots and pivot 20 are equal, as above noted, the links 21 rock in unison with the links 18 about a common axis. The blade is thus moved to the position of Fig. 6, the end of the blade being fully withdrawn from the jaws 3.

When the pivot 20 is almost or substantially aligned with pivots 12a, the blade starts to rotate about pivot 20, causing arms 14 to rotate about their stationary pivots 12a. When the pivot 20 is exactly aligned with pivots 12a, the links 21 stop moving while the blade continues to rotate about pivot 20 to the open position shown in Fig. 7. During this rotation of the blade while the pivot 20 remains stationary, the arms 14 and links 18 rotate in unison about a common axis.

It will be seen that arms 14 and the links 15 and 18 support the blade while the links 21 serve as an additional support for the blade and also control the movement of the blade. Essentially the pivot 20 is moved from the position shown in Fig. 5 to that of Fig. 7 and then the blade is ro-

tated about this pivot. All the while, the arms and links cooperate to support the blade and control its movement.

The closing operation of the switch is, of course, just the reverse of the opening operation and will be clearly understood from the above description.

While it is preferred to employ the two arms 14 and the two links 18 so as to provide a mechanically strong balanced structure, it will be apparent that the arms 14 are functionally one and the same element, as are also the links 18. The same is true of the links 21. In some instances, it may be desired to employ a single arm or link instead of a pair of arms or links. Essentially the structure comprises a pivoted arm 14 having a stationary pivot, a pair of spaced links 15 and 18 connected between said arm and the switch blade, and another link 21 having a stationary pivot and connected to the blade pivot 20 of one of the aforesaid links.

It will be apparent that the invention provides a switch structure comprising a novel combination and arrangement of arms and links which are positive and simple in operation. Such structure avoids the use of cams, wedges and other devices, which are prone to stick, particularly in bad weather, and sometimes become inoperative. Obviously, the accumulation of ice or other deleterious conditions cannot prevent the operation of the switch, for the elements employed are capable of forceful action and operation in spite of such conditions. It will be apparent that the invention is not limited to the specific structure shown but is capable of various modifications.

35 I claim:

1. In an electric switch, a support, an arm rotatably mounted on said support, a pair of spaced links pivotally attached to said arm, a switch blade pivotally attached to said links so as to rock said links on said arm during longitudinal movement of the blade, the blade being rotatable about a pivot of one of said links, and another link pivotally connected to said support and to said blade.

40 2. In an electric switch, a support, an arm rotatably mounted on said support, a pair of spaced links pivotally attached to said arm, a switch blade pivotally attached to said links so as to rock said links on said arm during longitudinal movement of the blade, the blade being rotatable about a pivot of one of said links, and another link pivotally connected to said support and to said pivot.

45 3. In an electric switch, a support, an arm pivotally mounted on said support, a pair of spaced links pivotally attached to said arm, a switch blade pivotally attached to said links, said links rotating about their pivots on said arm when the switch blade is moved longitudinally, and another link pivotally mounted on said support and pivotally attached to said blade so as to rotate about its pivotal mounting during the longitudinal movement of said blade, the blade being rotatable about the pivot connection of said 50 other link when in retracted position while said arm rotates about its mounting pivot.

55 4. In an electric switch, a support, an arm pivotally mounted on said support, a switch blade, a pivot on said blade, a link pivotally attached to said arm and to said blade pivot, a stationary pivot mounted on said support, a link pivotally attached to said blade pivot and to said

stationary pivot, and another link pivotally attached to said arm and to said blade.

5 5. In an electric switch, a support, an arm pivotally mounted on said support, a pair of spaced links pivotally attached to said arm, a switch blade pivotally attached to said links, the link nearest the mounting pivot of said arm being equal in radial length to the distance of its pivot on said arm from said mounting pivot, said links rotating about their pivots on said arm when the 10 switch blade is moved longitudinally, and another link pivotally mounted on said support and pivotally attached to said blade at the pivot of the said link nearest the arm mounting pivot, said other link being equal in length to the said distance whereby to rotate about its pivotal mounting in unison with the said link nearest the arm mounting pivot during the longitudinal movement of said blade, the blade being rotatable about the pivot connection of said other link 15 when in retracted position while said arm rotates about its mounting pivot.

6. In an electric switch, a support, a stationary pivot mounted on said support, an arm rotatably mounted on said pivot, a pivot on said arm, a switch blade, a pivot on said blade, a link connected between said arm pivot and said blade pivot, the distance between the axis of said stationary pivot and the axis of said arm pivot being equal to the distance between the axis of said 30 arm pivot and the axis of said blade pivot, a second stationary pivot mounted on said support, a second link connected between said second stationary pivot and said blade pivot, the distance between the axis of said second stationary pivot 35 and said blade pivot being equal to the aforesaid distances, and a third link pivotally connected between said arm and said blade.

7. In an electric switch, a support, a pair of spaced axially aligned pivots on said support, a switch blade, a pivot on said blade, a pair of arms rotatably mounted on said support pivots, a pair of axially aligned pivots one on each of said arms, a pair of links connected respectively between said arm pivots and said blade pivot, another pivot on said support, another link connected between said other support pivot and said blade pivot, and another link pivotally connected between the ends of said arms and said blade.

40 8. In an electric switch, a support, an arm pivotally mounted on said support, a switch blade, a pair of spaced links pivotally connected between said arm and said blade, and forming with the arm and the blade a quadrilateral, and means arranged cooperatively with said arm and said 45 links to support the blade and control its movement.

9. In an electric switch, a support, an arm pivotally mounted on said support, a switch blade, a pair of spaced links pivotally connected between said arm and said blade, and forming with the arm and the blade a quadrilateral, and another link pivotally connected between said support and said blade.

45 10. In an electric switch, a support, an arm pivotally mounted on said support, a switch blade, a pair of spaced links pivotally connected between said arm and said blade, and forming with the arm and the blade a quadrilateral, and another link pivotally connected between said support and the blade pivot of one of the aforesaid 50 links.

EDWIN STEWART.
